UNITED STATES PATENT OFFICE

CHARLES LOFMAN, OF CHICAGO, ILLINOIS, ASSIGNOR TO S. KARPEN & BROS., OF CHICAGO, ILLINOIS, A CORPORATION OF WEST VIRGINIA

SPRING-STRUCTURE

Application filed November 2, 1931. Serial No. 572,646.

The present invention relates particularly to spring-structures adapted for use for various purposes, as for use in mattresses, bed springs, or for upholstery purposes.

5 The invention is illustrated in a preferred embodiment in the accompanying drawing, in which—

Fig. 1 is a broken plan view of a spring-structure embodying the invention; Fig. 2, 10 an enlarged broken vertical sectional view taken as indicated at line 2 of Fig. 1; Fig. 3, a broken sectional view taken as indicated at line 3 of Fig. 2; and Fig. 4, a view similar to Fig. 2, but illustrating a modification.

15 It may be stated preliminarily that the present invention constitutes an improvement over the construction shown in Karpen and Lofman application, Serial No. 546,078, filed June 22, 1931.

20 In the illustration given, the spring-structure is shown as comprising rows of upholstery springs A and helical connectors B connecting the end-rings of the upholstery springs. Marginal helical connectors B' are 25 illustrated. They may be omitted, if desired, or they may have substituted therefor any suitable form of marginal binding.

The end-rings of the upholstery springs are designated A'.

30 Each of the end-rings is shown provided at diametrically opposite points with an elongated depression 1 adapted to serve as a connecting-member, or hinge-member. The metal of the end-ring is offset down- 35 wardly or inwardly so as to lie below or back of the plane of the end-ring.

40 Each spiral connector B is disposed below the plane of the end rings and serves to connect together two rows of springs and at the same time to secure the members of each row in properly spaced relation.

The manner in which the spiral connector is threaded into engagement with the depressed hinged-portions of the end-rings is 45 important. A typical arrangement is illustrated in the left hand portion of Fig. 2, which shows one of the intermediate connecting points in the spring-structure, while 50 the right-hand portion of Fig. 2 shows the

arrangement which is preferably employed at the end of the spiral connector.

It will be noted by reference to the left-hand portion of Fig. 2, that the depressed hinge-member 1 of one end-ring is slightly staggered with reference to the hinge-member 1 of the other end-ring. The arrangement is such that a single convolution, designated 2, of the connector engages both hinge-members, while a pair of convolutions 2^a of the connector engages each hinge-member, alone.

At the right-hand portion of Fig. 2, it appears that two convolutions 2^b of the connector engage both hinge-members of the end-rings, while a single convolution 2^c engages each hinge-member individually. At the left-hand portion of Fig. 2, it will be noted that three convolutions of the connector engages each hinge-member, but that one (the middle) convolution is common to both hinge-members. The result is that the end-rings are effectively locked against shifting longitudinally with relation to the connector. At the same time, a free-hinging action is permitted. This form of connection is extremely desirable, also for the reason that when the springs are heavily compressed at a given point, there is no danger of the hinge becoming dislocated. In other words, it always will return to its proper position.

55 In the modification shown in Fig. 4, one end-ring is designated A², and the other end-ring is designated A³. The depressed hinge-members are designated 3 and 4, respectively. In this case two convolutions 5 of the connector engage both hinge-members, and single convolutions 6 engage single hinge-members. This illustrates a form of connection for use throughout the body of the spring-structure to take the place of that shown in the left-hand portion of Fig. 2. It will be noted that the construction shown in Fig. 4 corresponds with that shown in 95 the right-hand portion of Fig. 2, which ordinarily is employed at the end of a connector.

100 The improved construction possesses the advantage that the spiral connectors are

located below or inside of the plane of the end-rings, so that no projection above the plane of the end-rings occurs. Thus, danger of injuring the mattress is largely obviated. A further feature of advantage is the peculiar interlock hinge-connection between the hinge-members and the spiral connector, due to miss-matching or slightly staggering the hinge-members with relation to each other, but still leaving them so that at least one common convolution of the connector will engage both hinge-members, while another convolution, or convolutions, will engage hinge-members independently.

15 The foregoing detailed description has been given for clearness of understanding only, and no unnecessary limitations should be understood therefrom, but the appended claim should be construed as broadly as 20 permissible, in view of the prior art.

What I regard as new, and desire to secure by Letters Patent, is:

A spring-structure comprising parallel rows of upholstery springs, having end-rings 25 disposed substantially in contact at lines between said rows, said end-rings having depressed hinge-members disposed below the plane of the end-rings and helical connectors arranged between said rows below the plane 30 of the end-rings and having threaded engagement with said hinge-members, the hinge-members being of the same length and partially miss-matched and at least one convolution of the connector engaging both 35 hinge-members of a pair and one or more convolutions engaging each individual hinge-member only.

CHARLES LOFMAN.
